VARIABLE-SPEED-TRANSMITTING DEVICE.

1,115,971.

Specification of Letters Patent.

Patented Nov. 3, 1914.

Application filed May 26, 1913. Serial No. 769,853.

To all whom it may concern:

Be it known that we, MILES E. PEARSON and LESTER F. LANE, citizens of the United States, residing at Seattle, in the county of 5 King and State of Washington, have invented certain new and useful Improvements in Variable-Speed-Transmitting Devices, of which the following is a specification.

10 This invention relates to power transmission devices.

The object of the invention is the provision of mechanism of this character which is capable of driving two machines at various 15 relative speeds.

The invention consists in the novel construction and adaptation of parts, as will be hereinafter described and claimed.

In the accompanying drawings, Figure 1 20 is a plan view with parts shown in section of an embodiment of our invention applied to the prime movers of a kinetoscope and graphophone. Fig. 2 is a vertical longitudinal section of the same with the friction-pinions controlling devices shown in different positions from where they are illustrated in Fig. 1.

Referring to the drawings, 5 designates a 25 motor which is employed for rotating a disk wheel 6 at suitable speed. Disposed transversely with respect to the axis of said wheel are axially aligned shafts 7 and 8 which are journaled in bearing-boxes 9 and are secured against endwise movements in 30 any suitable manner as, for example, by means of set collars 10 which are juxtaposed with the ends of the boxes. The shaft 7 is operatively connected with the arbor 11 of a graphophone, indicated by 12, through 35 the medium of an endless belt 13 passing about the driving and driven pulleys 14 and 15, respectively provided on the referred to shaft and the arbor. As illustrated, the other shaft, 8, constitutes the arbor for the 40 spool 16 whereupon is wound the film 17 of a moving-picture machine. The manner of connecting the aforesaid shafts with the respective machines may, however, be varied and forms no part of the present invention.

45 The shafts 7 and 8 are each provided with a key-way 18 to receive feathers 19 provided within the hubs 20 and 21 of friction-pinions 22 and 23 which are mounted upon the respective shafts. These pinions are of

suitable diameters to make peripheral engagement with the adjacent face of the disk wheel and serve as agents for transmitting motion from the power driven disk to each of the shafts.

Seated in annular grooves provided in the respective pinion bosses are collars 24 having radially protruding horns 25 which are engaged in the slotted bifurcated arms 26 and 27 of levers which are fulcrumed to a pin 28 rigidly connected to a standard 29. 60 The other arms 26¹ and 27¹ of the respective levers carry nuts 30 which engage the right and left-hand screw threads provided on a screw-shaft 31. A controlling arm 32 is pivotally connected to the pin 28 and is 65 operatively connected to the screw shaft by means of horns 33 which engage the latter between peripheral ridges 34 provided thereon. The arm 32 is provided with a shoulder 35 and terminates in a screw-threaded stud 36 which extends through a slot 37 provided in a stationary frame 38 of arcuate shape. Fitted upon said stud is an internally threaded handle 39 engaging screw-threads formed upon the stud whereby 70 the controlling arm may be clamped to the frame at selected positions.

40 represents a hand-wheel provided on the screw-shaft for rotating the same.

The operation of the invention is as follows: When the wheel 6 is rotated the friction pinions 22 and 23 are driven thereby at speeds proportional to the distances of the same from the axis of the driving wheel. Should the pinions be at equal distances 85 from the wheel-center they would obviously be both rotated at the same speed. Such speed may, however, be varied relatively to the driving wheel by causing the pinions to approach or be further moved from each 90 other. Such regulation of the pinions is accomplished through the medium of the screw-shaft 31 which, upon being properly rotated, will impart motion to the nuts 30 which, in turn, cause the associated pinion-carrying levers to be opened or closed with respect to each other, in a manner corresponding to the action of the member's of a pair of scissors. When the pinions are to be driven at different speeds they are 100 shifted upon their respective shafts so that the pinion which is to have the greater speed will be presented in closer proximity

to the periphery of the wheel 6. Such regulation of the pinions is accomplished through the office of the controlling arm 32 in cooperation with the levers which are 5 operatively connected by means of the screw-shaft 31 and nuts 30. The handle 39 is first turned to release the arm 32, whereupon the latter is swung by the operator in one lateral direction or the other resulting 10 in the pinions being swung in a contrary direction diametrically across the face of the wheel 6. The devices thus influenced may then be secured in adjusted position by clamping the arm 32 to the frame by means 15 of the handle 39.

From the foregoing, it is evident that the speeds of the shafts 7 and 8 may be changed with respect to the driving wheel but unvaried with respect to each other by regulating 20 the separation of the pinions through the agency of the screw-shaft 31; while the speeds of the referred to shafts may be varied with respect to each other by shifting said pinions through the agency of the lever arm 32, the pinions being both moved in 25 the same axial direction.

In the application of the invention for use with a kinetoscope and sound producing instrument, it is apparent that the operator can readily reduce or accelerate the 30 speeds of the two instruments in unison or may alter their speeds to compensate for or correct any differences in register therebe-

tween to give reproductions in substantially correct synchronism.

35

What we claim, is—

1. The combination with a driving disk, two axially alined shafts arranged transversely to the axis of said disk, pinions splined to the respective shafts and in frictional engagement with said disk, levers operatively connected with the respective pinions, means for adjusting said levers for regulating the positions of the pinions with respect to each other, and a controlling 40 means operatively connected with said levers whereby the pinions may be adjusted to regulate their positions with respect to the disk only.

2. In apparatus of the class described, 50 the combination of two driven elements, a single driving element therefor, means for regulating the relative positions of the driven elements to vary the speed ratios thereof, and means for regulating the positions of the driven elements with respect to the driving element to vary the speed of the driven elements without disturbing the selected speed ratios thereof.

Signed at Seattle, Wash., this 15th day of 60
May 1913.

MILES E. PEARSON.
LESTER F. LANE.
